FIG. 1 is a front perspective view of a pump and generator assembly according to the present design;

FIG. 2 is a rear perspective view of the pump and generator assembly of FIG. 1;

FIG. 3 is a front view of the pump and generator assembly of FIG. 1;

FIG. 4 is a right side view of the pump and generator assembly of FIG. 1;

FIG. 5 is a left side view of the pump and generator assembly of FIG. 1;

FIG. 6 is a rear view of the pump and generator assembly of FIG. 1;

FIG. 7 is a top view of the pump and generator assembly of FIG. 1; and,

FIG. 8 is a bottom view of the pump and generator assembly of FIG. 1.

The broken lines depicting the screws, the knobs, the ports, and portions of the radiofrequency ablation pump and generator assembly are included for the purpose of illustrating environmental subject matter and form no part of the claimed design.
